UNITED STATES PATENT OFFICE

163,657

BOOKMARK

Anna V. Wagner, Chicago, Ill.

Application March 14, 1951, Serial No. 14,478

Term of patent 7 years

(Cl. D6—1)

To all whom it may concern:

Be it known that I, Anna V. Wagner, a citizen of the United States, residing at Chicago, in the county of Cook, and State of Illinois, have invented a new, original, and ornamental Design for a Bookmark, of which the following is a specification, reference being had to the accompanying drawing, forming part thereof, in which—

Fig. 1 is a front face view of the bookmark, showing my new design;

Fig. 2 is a rear face view of the bookmark; and

Fig. 3 is an edge view as observed from the right of Fig. 1.

I claim:

The ornamental design for a bookmark, substantially as shown.

ANNA V. WAGNER.
